(57) **CLAIM**

The ornamental design for a notebook computer, as shown and described.

DESCRIPTION

FIG. 1 is a perspective view of the notebook computer according to an embodiment of the present design, an elongated touch screen being positioned at a top of a keyboard, and buttons, sensors and/or touch screens being positioned at both sides of the elongated touch screen;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the notebook computer according to another embodiment of the present invention, an elongated touch screen being positioned at a top of a keyboard, and buttons, sensors and/or touch screens being positioned at both sides of the elongated touch screen;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the notebook computer according to another embodiment of the present invention,

(Continued)

an elongated touch screen being positioned at a top of a keyboard, and buttons, sensors and/or touch screens being positioned at both sides of the elongated touch screen; FIG. 16 is a front view thereof; FIG. 17 is a rear view thereof; FIG. 18 is a left side view thereof; FIG. 19 is a right side view thereof; FIG. 20 is a top view thereof; and, FIG. 21 is a bottom view thereof.

The broken lines shown in the drawings illustrate portions of the notebook computer that form no part of the claimed design.

1 Claim, 21 Drawing Sheets
